GAUGE MEANS FOR FITTING SCREENS TO
CARD CYLINDERS

Olin S. Elliott, Greenville, S. C.

Application April 20, 1950, Serial No. 157,073

3 Claims. (Cl. 33—180)

1

This invention relates to a gauge means for fitting a screen to the main cylinder of a carding machine and it is an object of the invention to provide such a means whereby the desired curvature of a screen and of the clothing may be accurately determined with respect to the circumference of the cylinder.

Furthermore, it is an object of the invention to provide a means of this kind including two gauging elements, one for use with the said clothing and the second for direct use with the screen or screens to be fitted about the periphery of the cylinder from one or both ends of said clothing and wherein the setting of the second gauging element is made directly from the first gauging element.

The invention consists in the details of construction and in the combination and arrangement of the several parts of my improved means for fitting a screen as aforesaid whereby certain advantages are attained, as will be hereinafter more fully set forth.

In order that my invention may be better understood, I will now proceed to describe the same with reference to the accompanying drawings, wherein:

Figure 1 is a fragmentary diagrammatic view in end elevation showing an initial step in the fitting of a screen to the main cylinder;

Figure 2 is a view in side elevation of the two gauging elements, illustrating the settings of one gauge from the other;

Figure 3 is a view in top plan of Figure 2;

Figure 4 of an enlarged sectional view taken substantially on the line 4—4 of Figure 3;

Figure 5 is a sectional view taken substantially on the line 5—5 of Figure 4; and

Figure 6 is a view partly in section and partly in elevation illustrating the step of applying a gauging member to a screen for setting the same.

As illustrated in the accompanying drawings, A denotes a conventional type of main cylinder of a carding machine, around the upper peripheral portion of which the usual clothing (not shown) is disposed to cooperate with the teeth on the periphery of the cylinder for the straightening out and laying of the fibers to be carded parallel as they pass between the clothing and the cylinder. Associated with cylinder A and applied clothing are the usual screens D, generally two in number and which, when in use, are supported in close proximity to the ends of the clothing and from below the cylinder A. As these several parts are well known and form no particular part of the invention, it is not believed

that a more detailed description or illustration is necessary.

The fitting of a screen D is important when applied in connection with a new clothing after it has been installed relatively to the cylinder. The invention as herein comprised involves two steps for determining the arc of curvature, first, of the applied clothing and, second, performing the screens D accordingly, which can readily be accomplished by pounding as required.

To put the method into effect, two gauging elements X and Y are employed, the element X being used directly in connection with the applied clothing B and the element Y being directly used in connection with the screen D to be fitted.

The gauging element Y is of a length closely approximating the length of a screen D as illustrated in Figure 6 of the drawings. The element Y as herein disclosed is longitudinally disposed on a segment of a circle. The extremities of the body 1 are provided with the relatively long heads of duplicate structure both as to form and dimensions and these heads 2 extend laterally and outwardly from the body 1 from the out-bow side of the body 1. The outer faces 3 are smooth and unobstructed and outwardly curved from end to end or in a direction lengthwise of the body 1 of the element Y. These arcuate out-bow faces 3 are also of the same radius and substantially the same radius as the applied clothing.

Freely disposed through the body 1 at a point between the heads 2 is an elongated shank 4 provided at its outer extremities with an enlargement or button 5. Interposed between the enlargement or button 5 and the adjacent portion of the member 1 is an expansible member 6 herein disclosed as a coil spring of required tension surrounding the outer portion of the shank 4. This expansible member or spring 6 serves to constantly urge the shank 4 toward the limit of its normal outward movement. This normal position of the shank 4 is determined by contact of the member 1, with the stop member 7 fixed to and surrounding the shank 4 inwardly of the member 1.

The shank 4 is passed through the center of the element 1 and the stop member 7 and is threaded at its inner end as at 8, which end engages with a socket 9, in the central portion of an elongated block 10, the longitudinal axis of which is disposed lengthwise of the member 1. The block 10 is held against swinging or turning movement around the end portion 8 of the shank 4 by a pair of spaced pins 11 projecting in parallel relation from the inner face of the member 1.

and engaging in bores 12, opening through the block 10. The pins 11 are at opposite sides of the shank 4 and equidistantly spaced therefrom with said pins 11 freely and snugly engaged within the bores 12 opening through the block 10. Upon requisite turning of the shank 4, the block 10 may be adjusted, as desired, toward or from the body 1 for a purpose to be hereinafter explained.

The outer face 14 of the block 10 is smooth 10 and unobstructed and is disposed from end to end on an outward curvature or outbow of the same radius as the faces 3 of the heads 2.

The element X is substantially the same dimensions as the element Y. The elongated body 15 is also arcuate or inbowed from end to end on its inbowed side and is provided at its extremities with the laterally directed heads 16 having their inner faces 17 disposed from end to end of the heads 16 on a radius the same as 20 the radius of the faces 3 of the heads 2 of the body 1 of the male gauge or element Y.

Freely disposed through the body 15 is a shank 18 which is constantly urged toward and normally maintained at the limit of its outward 25 movement by the expansible coil spring 19 encircling the shank 18 and interposed between an enlargement or button 20 at the outer end portion of the shank 18. The normal outward position of the shank 18 is determined by the surrounding stop member 21 fixed to the shank 18 and contacting the adjacent inner face portion of the body 15 of the element X. The portion 22 of the shank 18 outwardly from the stop member 21 threads into a socket 23 arranged at 30 the central portion of an elongated block 24. The longitudinal axis of the block 24 is disposed lengthwise of the body 15. At opposite sides of the socket 23 and equidistantly spaced therefrom are the sockets or openings which snugly 40 and slidably receive the parallel pins 26 carried by the body 15 to hold the block 25 against turning movement around the shank 18.

The outer face 27 of the block 24 is also smooth and unobstructed and longitudinally curved on 45 an inbow radius the same as the radii of the faces 17 of the heads 16.

In fitting a screen D, a gauge element X is disposed circumferentially with respect to the cylinder A, with the faces 17 of the heads 16 in 50 close contact with the teeth on the periphery thereof. The shank 8 is then rotated in a direction to bring the face 27 of the block 24 into close engagement with the card clothing (Figure 1). After this adjustment of the gauge element 55 X, the same is applied to the gauge element Y (Figure 2) with the faces 3 of the heads 2 of the element X in close contact with the faces 17 of the heads 16 of the element X. The shank 4 on the element Y is then rotated in a direction to bring the face 14 of the block 10 into close engagement with the face 27 of the block 24 of the gauge element X. The gauge element Y is then transferred to the screen D (Figure 6) with

the element Y disposed lengthwise thereof. When the faces 3 of the heads 2 and 14 respectively of the element Y and block 10 have close contact from end to end with the inbow side or face of the screen D, said screen will be of required curvature for the desired fitting to the card cylinder A or as the case may be, to the clothing Y. When upon application of the gauge element Y to the inbowed side of the screen D, there is not the desired end to contact with the faces 2 and 14, the screen D is to be pounded with a suitable implement until such desired contacts are obtained.

It is of advantage to have the blocks 10 and 24 to one side of the longitudinal center of its body 1 or 15, respectively, as a finer adjustment of the screen D may be obtained. After a first fitting with the gauge element Y, said element may be reversed.

I claim:

1. Gauge means for checking the curvature of a screen of a carding machine with respect to the curvature of the applied clothing of the main cylinder of the machine, comprising two elongated elements of substantially the same length, laterally disposed and relatively long heads carried by the extremities of the elements, the outer faces of the heads being curved in a direction lengthwise of the elements, the curvatures of the two elements being of the same radius and substantially the same as the radius of the applied clothing, the arcuate faces of the heads of one element being on inbows and the arcuate faces of the heads of the second element being on outbows, blocks carried by the central portions of the elements at the same sides thereof as the heads, and means for moving each of the blocks toward or from its associated element, the outer face of each block being curved in a direction lengthwise of the associated elements on the same radius as the radii of heads and in the same direction of curvature.

2. In a means as set forth in claim 1, resilient means constantly urging the blocks toward the elements.

3. In a means as set forth in claim 1, parts for holding the blocks against displacing movement transversely of or across the element.

OLIN S. ELLIOTT.
